CENTERING JIG

Roger W. Baker, Mishawaka, Ind., assignor to
George F. Martin, Jr., Elkhart, Ind.

Application January 16, 1939, Serial No. 251,273

4 Claims. (Cl. 77—62)

This invention relates to gages or jigs and more particularly to a centering jig for use with a drill or other tool.

An object of this invention is to provide an improved jig for use with a tool such as a drill or the like which is so constructed that it can be readily engaged with either a round, square or rectangular article so as to securely hold a drill or other tool relative to the article.

Another object of this invention is to provide a jig of this kind which is capable of ready adjustment so that the jig can be easily and quickly adjusted to engage articles of various sizes and types.

A further object of this invention is to provide a jig of this kind which is provided with a bushing structure in the center thereof, the bushing structure being pressed or otherwise firmly mounted within a supporting block so that where it is desired to use different sizes of tools or drills, which are adapted to pass through the bushing, the block may be engaged with the remaining structure which embodies a different size bushing.

A still further object of this invention is to provide a jig of this kind which may be used to center a tool relative to an article to be worked upon, the jig being so constructed that it may engage either the interior or exterior of the article which is being worked upon.

To the foregoing objects and to others which may hereinafter appear, the invention consists of the novel construction, combination and arrangement of parts as will be more specifically referred to and illustrated in the accompanying drawing, wherein is shown an embodiment of this invention, but it is to be understood that changes, modifications and variations may be resorted to which fall within the scope of the invention as claimed.

In the drawing:

Figure 1 is a perspective view of a jig constructed according to an embodiment of this invention.

Figure 2 is a sectional view taken on the line 2—2 of Figure 1.

Figure 3 is a fragmentary sectional view taken on the line 3—3 of Figure 1, and

Figure 4 is a fragmentary sectional view taken on the line 4—4 of Figure 1.

Referring to the drawing, the numeral 10 designates generally a supporting block which in the present instance, is constructed of metal and is provided with a pair of openings 11 therethrough.

The openings 11 are in parallel relation to each

other and are positioned one adjacent each side edge of the block 10 at a point below the center thereof. An elongated rod 12 which is provided with a flat upper surface 13 is adapted to engage through an opening 11 in the block 10 and is adapted to project beyond the adjacent ends of the block 10 as shown in the drawing. The rod 12 at one end thereof is provided with a depending lug 14 having an opening 15 therein within which one end of the rod 12 is adapted to engage. The rod 12 in the present instance is adapted to be pressed or otherwise firmly mounted in the opening 15 of the lug 14 and is adapted to extend downwardly at right angles to the length of the rod 12. Each rod 12 is adjustably secured in the block 10 by means of a set screw 16 which engages in a threaded opening 17 provided in the block 10. The set screw 16 is of the type wherein a countersunk socket is provided in the outer end thereof in which a key or plug wrench is adapted to engage.

The block 10 is also provided with a second pair of openings 18 which extend in parallel relation to each other through the block 10 and at right angles to the openings 11. The openings 18 are positioned above the openings 11 and an elongated rod 19 similar to the rod 12 is adapted to engage in an opening 18. The rods 19 are substantially of the same length as the rods 12 and on the under side thereof each rod 19 is provided with a flat longitudinally extending face 20. The block 10 is provided with a threaded opening 21 for each rod 19 in which a set screw 22 is threaded and engages the flattened surface 20 of the rod 19 so as to adjustably hold a rod 19 relative to the block 10. The set screws 22 are similar to the set screws 16, being provided with a countersunk socket in which a suitable plug wrench is adapted to engage. The rods 19 at one end thereof are provided with a lug 23 having an opening 24 in which the rod 19 engages. The rod 19 may be pressed or otherwise firmly positioned in the opening 24 so that the lugs 23 will be disposed in a vertical position when the block 10 is in a horizontal position. The set screws 16 and 22 are adapted to, at all times, hold the rods 12 and 19 with the lugs 14 and 23 thereof at right angles to the upper face of the block 10.

The block 10 in substantially the center thereof is provided with an opening 25 therethrough in which a pair of bushing members 26 are adapted to engage. The bushing members 26 are pressed or otherwise firmly mounted in the block 10 and in the present instance, there are two of these bushings 26 which are pressed into

the block 10 from the opposite faces thereof. The bushings 26 are provided with a bore 27 therethrough in which a tool such as a drill or punch is adapted to engage so as to hold the 5 drill or tool in an operative position.

In the use of this jig the rods 12 and 19 are adjusted relative to the block 10 and to each other so that the axis of the bore 27 will be positioned properly relative to the article which 10 is being worked upon. The lugs 14 and 23 may engage the exterior surface at one end of a cylinder or other round object or if desired, these lugs 14 and 23 may engage within the interior 15 of a cylinder. It will also be understood that these lugs 14 and 23 may engage adjacent sides of a square or rectangle so as to position the axis of the bore 27 of the bushings 26 in the desired location relative to the article which is being worked upon. The adjustment of the rods 20 12 and 19 is effected by adjustment of the set screws 16 and 22 so that these rods 12 and 19 may have the lugs 14 and 23 respectively projecting beyond the block 10 for an equal distance or if desired, the rods 12 may project beyond 25 the block 10 for a distance different from the rods 19, this adjustment being dependent on the location of the hole which is to be drilled in the article to be worked upon. This jig is of an exceedingly simple construction so that it can be 30 manufactured at a relatively small cost and due to the ready adjustment of the several parts thereof the jig can be used for various articles and when once adjusted will accurately position the axes of the bushings 26 in the proper relation 35 to the article which is being worked upon. While I have shown the bushings 26 as being firmly mounted in the block 10, if desired, these bushings may be releasably mounted therein by well known means.

40 What I claim is:

1. A jig as set forth comprising a block member provided with pairs of right angularly related openings therethrough disposed parallel with opposite faces of the block, rods disposed in said openings and projecting beyond the adjacent edges of the block, threaded means clamping said rods in said openings, and right angular-

ly disposed article engaging members carried by an end of each rod.

2. A jig as set forth comprising a block member provided with right angularly related openings therethrough disposed parallel with opposite faces of the block, rods disposed in said openings and projecting beyond the adjacent edges of the block, each of said rods having a flat longitudinally extending surface, a right angularly disposed article engaging member carried by one 10 end of each rod, and clamping means carried by the block engaging the flat surfaces of the rods to adjustably secure said rods in said openings while simultaneously holding said article engaging members at right angles to the opposite faces 15 of the block.

3. A jig as set forth comprising a block member provided with right angularly related openings therethrough disposed parallel with opposite faces of the block, rods disposed in said openings and projecting beyond the adjacent edges of the block, each of said rods having a flat longitudinally extending surface, a right angularly disposed article engaging member carried by one 20 end of each rod, threaded clamping means carried by the block engaging the flat surfaces of the rods to adjustably secure said rods in said openings while simultaneously holding said article engaging members at right angles to the opposite faces 25 of the block, said block having a centrally disposed opening transversely therethrough, and a bushing member engaging in said central opening.

4. A jig as set forth comprising a block, a pair of parallel rods slidable through said block, a 35 right angularly disposed member fixed to each rod at one end thereof, a second pair of parallel rods slidable through said block and disposed at right angles to said first pair of rods, a right angularly disposed member fixed to one end of 40 each of said second pair of rods, clamping means carried by said block and engaging said rods for adjustably securing said rods relative to said block, and a tool guiding bushing carried by said block.

ROGER W. BAKER.
